UNITED STATES PATENT OFFICE

1,937,909

HEATING SYSTEM

Arthur E. Paige, Philadelphia, Pa., assignor to
John Wood Manufacturing Company, Conshohocken, Pa., a corporation of Pennsylvania

Original application January 18, 1928, Serial No.
247,696. Divided and this application Sep-
tember 25, 1930. Serial No. 484,326

5 Claims. (Cl. 237—8)

This is a division of my original application
Serial No. 247,696 filed January 18, 1928, for Let-
ters Patent of the United States for Improvement
in methods of heating and ventilating.

5 Structures hereinafter described including a
radiator, a fan, and a motor therefor, in com-
bination with a casing, are the subject matter
of my copending divisional application for Let-
ters Patent of the United States for Improve-
ment in heat exchange apparatus, Serial No.
412,972 filed December 10, 1929.

My invention relates to heating systems includ-
ing a furnace comprising a fuel burner in co-
operative relation with a container in which any
15 suitable heating fluid, for instance, steam or
water, may be heated; and conduits forming a
circulatory system leading from and returning
to said container and supplying said heating
fluid to a radiator or radiators, to heat the at-
20 mosphere local to the radiator surface. The pur-
pose and effect of my invention are to facilitate
and augment the transfer of heat from the ra-
diator surface to the adjacent atmosphere by
more rapid displacement of the air at such sur-
25 face than is possible by convection; and at a rate
variable with the heat supplied.

As hereinafter described, my invention in-
cludes means for facilitating and augmenting
the transfer of heat from a fluid supplied to a
30 radiator to the atmosphere adjacent to the ra-
diator, by utilizing power from the heating fluid
to operate a motor to forcibly circulate the air
relatively to the radiator, by means of a rotary
fan.

35 The typical heating system herein disclosed
includes a gas burning water heater and means
for maintaining a forced circulation of water
within the heating system, by an electrically con-
trolled pump; the operation of the device being
40 controlled by thermostatically operative means;
and the forced circulation of air thru the radiator
is effected by a motor included in a bypass short-
circuiting the radiator with which it is associ-
ated; so that the heating fluid is taken into the
45 motor from the supply conduit leading from the
heater to the radiator, and the exhaust from the
motor is discharged into the return pipe leading
from the radiator back to the heater.

50 My invention herein claimed includes the va-
rious novel features of construction and arrange-
ment hereinafter more definitely specified.

In said drawings; Fig. I is a diagram showing
a house heating system embodying my invention.

Fig. II is a vertical sectional view of one of
55 the radiator structures shown in Fig. I, taken on
the line II, II.

Fig. III is a plan sectional view of said struc-
ture, taken on the line III, III in Figs. I and II.

Fig. IV is a fragmentary sectional view of the
60 fluid motor indicated in Figs. I and II.

Fig. V is a fragmentary sectional view of a
modified form of fluid motor.

Referring to Fig. I; the house or other build-
ing comprising rooms or other inclosures 2 and
3, has, preferably in the cellar 4 thereof, the 65
heater 6 inclosing the burners 7 and 8 supplied
with gas from the conduit 9 under control of the
thermostatically operative valve in the casing 10.
Said valve casing carries the tubular thermo-
static element 11 extending within the water 70
conduit 12 which is connected with the pipe 14
thru which hot water is delivered from the cel-
lular heater units 16 which are supplied with
cold water thru the pipe 18. Said conduit 12 is
connected by pipes 20 with radiator units 21, 75
from which the water is returned thru pipes
23 to the pump 24 which is connected to said
pipe 18 and arranged to be operated by the elec-
tric motor 25, under control of the thermostati-
cally operative switches 27. Said pump is op- 80
erated to circulate the water thru the system
in the direction indicated by the arrows.

Referring to Figs. II, III and IV; each of said
radiators 21 comprises a cellular structure 30
which is a rectangular congeries of metal tubes 85
31 having enlarged polygonal ends 32 which fit
together and are sealed in connection with a
casing band 33 so as to form a cellular honeycomb
of thin metal walls and comprising separate pas-
sageways 35 for hot water or steam and 36 for 90
atmospheric air. Said radiator includes the in-
let port 38 and the outlet port 39 in communica-
tion with said passageways 35 for the heating
medium. The outer casing 40 for said congeries
31 forms a cold air inlet chamber 41 at the bot- 95
tom thereof, an intermediate chamber 42 con-
taining said cellular structure, and an upper
outlet chamber 43 for the heated air. The fluid
motor 45 is preferably mounted in said inlet
chamber 41 with a fan 46 arranged to force air 100
into said outer casing 40 thru the stationary
louvers 47 in the lower portion of said casing
and thru the passageways 36 in said congeries of
tubes, and out from the heated air chamber 43
into the surrounding atmosphere, thru the fo- 105
raminous panel or grill 49.

Said fluid motor 45 includes an outer casing 50
provided with ports 51 and 52 thru which the
heating fluid in the system circulates from the
pipes 20 to the pipes 23. Said casing 50 con-
tains the rotor 54, the blade 55, and the shaft
56 which latter is journaled in said casing and
in operative connection with said fan 46. Valves
57 and 58 may be provided local to said motor
casing to vary the relative volume of the heating 115
fluid which shall be directed to the radiator 21
and thru the motor 45. It is to be understood
that said valves may be adjusted to variably de-
termine the speed of rotation of the motor and
consequent air displacement effect of said fan 46 120

to attain the desired efficiency of transfer of heat from the radiator to the surrounding atmosphere; it being noted that such capacity should be increased and diminished in accordance with increase and decrease in the heat supplied to the radiator. Altho said fan 46 is indicated as in coaxial relation with said shaft 56, it is to be understood that it may be connected therewith by gearing so as to be rotated more rapidly than said shaft.

Altho I find it convenient to employ a fluid motor of the rotary type indicated in Fig. IV; any other suitable type of motor may be employed. For instance, Fig. V shows a fluid motor 59 of the reciprocatory type. The fan 46 may be mounted directly upon the shaft 60 or, as shown, the fly wheel 61 may be connected by a belt 62 with a pulley 63 on the shaft 65 which carries the fan 46. Said motor 59 may be included in multiple relation with a radiator 21 in a bypass from the supply pipe 20 to the exhaust return pipe 23 and be controlled by valves 57 and 58 as above described; but may be otherwise exhausted.

Therefore, I do not desire to limit myself to the precise details of construction, arrangement, or procedure herein set forth, as it is obvious that various modifications may be made therein without departing from the essential features of my invention, as defined in the appended claims.

3. I claim:

1. The combination with a radiator structure having separate passageways for a heating fluid and air; of conduits for heating fluids leading to and from said radiator structure; means to force air through the air passageways, including a rotary fan and a motor operatively connected with said fan; a pump connected into the system so as to force fluid through the fan motor; means to operate said fan motor by power from the heating fluid, including conduits leading to and from said fan motor, in multiple relation with said radiator conduits; a separate motor for said pump; and valve controlling means respectively in said radiator and motor conduits for varying the relative volumes of heating fluid respectively supplied to said radiator and fan motor; whereby said fan is operated at a variable speed which is determined by the rate of flow of the heating fluid through said pump, and all of the heating fluid utilized in operating said fan motor is returned into the radiator system to be reheated; and thermostatic means to control the operation of said pump motor in accordance with the temperature of the atmosphere local to said radiator; said controlling means being arranged to vary the speed of the pump motor inversely with the temperature local to the radiator structure.

2. The combination with a radiator structure having separate passageways for a heating fluid and air; of conduits for heating fluid leading to and from said radiator structure; means to force air through the air passageways, including a rotary fan and a motor operatively connected with said fan; a pump connected into the system so as to force fluid through the fan motor; means to operate said motor by power from the heating fluid, including conduits leading to and from said fan motor, in multiple relation with said radiator conduits; a separate motor for said pump; and valve controlling means, respectively in said radiator and motor conduits, to vary the relative volumes of heating fluid respectively supplied to said radiator and fan motor; whereby said fan is operated at a variable speed which is determined by

the rate of flow of the heating fluid through said pump, and all of the heating fluid utilized in operating said fan motor is returned into the radiator system to be reheated; wherein said pump is cooperatively connected in series relation with a plurality of such radiator fan motors by said conduits, and the pump motor is electrically energized and including electrical controlling means for said pump motor, said controlling means including a thermostat local to said radiator structure but remote from said pump motor; wherein the fan motors are connected in multiple with each other; said controlling means being arranged to vary the speed of the pump motor inversely with the temperature local to the radiator structure.

3. The combination with a radiator structure having separate passageways for a heating fluid and air; of conduits for heating fluid leading to and from said radiator structure; means to force air through the air passageways, including a rotary fan and a motor operatively connected with said fan; a pump connected into the system so as to force fluid through the fan motor; means to operate said fan motor by power from the heating fluid, including conduits leading to and from said fan motor, in multiple relation with said radiator conduits; an electric motor for said pump; valve controlling means, respectively in said radiator and motor conduits to vary the relative volumes of heating fluid respectively supplied to said radiator and fan motor; whereby said fan is operated at a variable speed which is determined by the rate of flow of the heating fluid through said pump, and all of the heating fluid utilized in operating said fan motor is returned into the radiator system to be reheated; and thermostatic means to control the operation of said pump motor in accordance with the temperature of the atmosphere local to said radiator; said controlling means being arranged to vary the speed of the pump motor inversely with the temperature local to the radiator structure.

4. In a heating system, the combination with a heater comprising a burner and a heating fluid container in cooperative relation therewith; of a radiator in spaced relation to said heater; conduits for conveying heating fluid from said heater to said radiator and returning the same; a pump in one of said conduits; an electric motor arranged to actuate said pump; a thermostat local to said radiator; an electric circuit connecting said motor with said thermostat to control said radiator; a fan local to said radiator for circulating air with respect thereto; a fluid motor operatively connected with said fan; conduits including said fan motor in multiple relation with said radiator conduits; and valve controlling means respectively in said radiator and motor conduits for controlling the relative volumes of heating fluid respectively supplied to said radiator and fan motor; whereby said fan is operated at a variable speed which is determined by the rate of flow of the heating fluid through said pump, and all of the heating fluid utilized in operating said fan motor is returned into the radiator system to be reheated.

5. A heating system as in claim 4, including a valve controlling the supply of fuel to the burner and a thermostatic device for controlling said valve inversely with the temperature of the heating fluid in a conduit between said heater and the radiator.

ARTHUR E. PAIGE.
